UNITED STATES PATENT OFFICE.

ELEAZER A. RANDALL, OF MONMOUTH, ILLINOIS.

STRINGED MUSICAL INSTRUMENT.

No. 818,289.

Specification of Letters Patent.

Patented April 17, 1906.

Application filed October 9, 1905. Serial No. 282,041.

To all whom it may concern:

Be it known that I, ELEAZER A. RANDALL, a citizen of the United States, residing at Monmouth, in the county of Warren and State of Illinois, have invented a new and useful Stringed Musical Instrument, of which the following is a specification.

My invention relates to improvements in stringed musical instruments having each a sound-box, and to that particular type or class of which belong guitars, mandolins, and the like; and the objects of the invention are to produce a symmetrical instrument of the character described in which the resonancy will be increased and the sound-waves rendered more intense, while at the same time the notes will be liquid and dulcet.

An instrument embodying the preferred constructive forms of and showing the mutual relationship and combinations of the parts forming the subject-matter of my improvements is illustrated in the accompanying drawings, in which the several parts are constructed, combined, and arranged in the best way now known to me. Obviously, however, some of these improvements may be used without the others without departing from the purview of my invention.

Like numerals refer to like parts in the several figures of the drawings, in which—

Figure 1 is a top plan; Fig. 2, a vertical central section; Fig. 3, a sectional view in the line 3 3 in Fig. 1; Fig. 4, a perspective, the neck and tailpieces not shown; Fig. 5, a top plan; Fig. 6, a bottom plan, and Fig. 7 a sectional view taken in the line 7 7 in Fig. 1.

Referring to the drawings, 1 represents a semispherical or bowl-shaped body or sound-box having a top or sound-board 2. 3, 4, 5, and 6 represent, respectively, the neck, strings, bridge, and tailpiece common to this class of instruments.

7 is a sound-conducting pipe and is glued or in any other preferred manner fixed to the inner portion of the sound-board in such manner that the perimeter of one of its ends surrounds the sound hole or opening thereof.

8 represent substantially parallel vibratory bars, glued or in any other preferred

manner fixed at their ends to the concavity 50 1^a of the body 1 longitudinally of the neck 3. Their median portions lie some distance from the lowermost portions of the body and are supported on a second bridge 9 transversely thereof, which bridge is of such height that it 55 will be firmly held in place by frictional contact in the usual manner of such devices.

10 and 11 are obliquely-disposed securing-braces and serve to prevent warping of the top 2, which latter may be secured to the 60 body in any preferred manner after the sound-amplifying devices are in place.

The pipe 7 is of such length that its lower portion will, when in place, rest firmly and securely upon the vibratory bars which 65 support it.

I have shown the body 1 of the instrument as an integral one, preferably turned from a block of suitable wood. This construction while economic of manufacture is strong, not 70 disposed to crack or check upon exposure or in use, will not warp, is free from angularity, and its exterior presents an admirable surface for ornamentation, as by carving or inlaying. The neck, head, keys, and other 75 parts of the instrument not herein particularly described may be of any preferred constructions.

Having thus described the nature of my invention and the best means of carrying the 80 same into effect, I claim as new—

1. A musical instrument of the class described, having a body provided with a sound-opening, a bridge seated within said body, vibratory bars fixed longitudinally to and 85 within said body, their median portions resting on said bridge, and a pipe or tube arranged to rest above said bridge between said bars and the top of the body.

2. In an instrument of the class described, 90 a neck and a sound-box, a bridge resting on the top of the box, a second bridge resting on the bottom thereof, vibratory bars resting thereon, their ends fixed to the body portion of the box, and a pipe or tube intermediate 95 the parallel bars and the top of the sound-box.

3. In a stringed instrument of the class

described, a sound - box provided with a sound-opening in the top thereof, a bridge arranged within the sound-box, vibrating bars resting thereupon, and a sound-conducting pipe resting upon said bars and its upper edge contacting said top around the sound-opening.

In testimony whereof I have hereunto set my hand this 30th day of September, 1905.

ELEAZER A. RANDALL.
